Primary Examiner — Wan Laymon*Assistant Examiner* — Clint A Samuel(74) *Attorney, Agent, or Firm* — Kim IP Law Group LLC(57) **CLAIM**

The ornamental design for a surgical striking apparatus, as shown and described.

DESCRIPTION

FIG. 1 is a first perspective view of a surgical striking apparatus in accordance with the new design;

FIG. 2 is a front view of the surgical striking apparatus of FIG. 1;

FIG. 3 is a rear view of the surgical striking apparatus of FIG. 1;

FIG. 4 is a right side view of the surgical striking apparatus of FIG. 1;

FIG. 5 is a left side view of the surgical striking apparatus of FIG. 1;

FIG. 6 is a top view of the surgical striking apparatus of FIG. 1;

FIG. 7 is a bottom view of the surgical striking apparatus of FIG. 1; and,

FIG. 8 is a second perspective view of the surgical striking apparatus of FIG. 1, shown in an alternate configuration. In the drawings, the broken lines illustrate portions of the surgical striking apparatus that form no part of the claimed design.
